US0D1051228S

(12) **United States Design Patent** (10) Patent No.: **US D1,051,228 S**
(45) Date of Patent: ** *Nov. 12, 2024

(54) **GAME BOARD AND GAME PIECE SET**

(71) Applicant: **SMART, naamloze vennootschap**,
Kontich (BE)

(72) Inventor: **Rein Lambrichts**, Hasselt (BE)

(*) Notice: This patent is subject to a terminal disclaimer.

(**) Term: **15 Years**

(21) Appl. No.: **35/515,091**

(22) Filed: **Jun. 14, 2022**

(80) **Hague Agreement Data**

Int. Filing Date: **Jun. 14, 2022**

Int. Reg. No.: **DM/223101**

Int. Reg. Date: **Jun. 14, 2022**

Int. Reg. Pub. Date: **Sep. 9, 2022**

(30) **Foreign Application Priority Data**

Dec. 15, 2021 (EM) 008799100-0003

Primary Examiner — George J Ulsh

Assistant Examiner — Andrea Marie McKay

(57) **CLAIM**

The ornamental design for a game board and game piece set as shown and described.

DESCRIPTION

- 1.1 : Top perspective view
- 1.2 : Right elevation view
- 1.3 : Left elevation view
- 1.4 : Front elevation view
- 1.5 : Back elevation view
- 1.6 : Top plan view
- 1.7 : Bottom plan view
- 1.8 : Bottom perspective view
- 2.7 : Bottom plan view
- 2.8 : Bottom perspective view
- 2.9 : Top perspective view
- 2.10 : Right elevation view
- 2.11 : Left elevation view
- 2.12 : Front elevation view
- 2.13 : Top plan view

1 Claim, 15 Drawing Sheets
